UNITED STATES PATENT OFFICE

ALBERT HOLLEN, OF MAYNARD, MINNESOTA

LATCH FOR BARN DOORS

Application filed March 15, 1929. Serial No. 347,269.

This invention relates to a lock or latch device for a door and while the device is applicable to various types of doors it particularly is designed for heavy doors, such as barn doors or garage doors. In barns and other buildings where there is heat or moisture inside, it often happens that in cold weather frost and ice collect on the outside of the building and doors and this frost and ice often freezes to the parts of the door latch so that it is difficult or impossible to operate the same.

It is an object of this invention to provide a very simple and efficient latching means for a door such as a barn door and one which comprises very few parts.

It is a further object of the invention to provide a simple and efficient form of latching mechanism for a door so constructed and arranged that water or moisture can collect and freeze on the latch or door in cold weather without interfering with the operation of the latch.

It is still another object of the invention to provide a latching mechanism for a door comprising a combined spring and latching bar adapted to engage a keeper with ample means for operating said bar.

It is more specifically an object of the invention to provide latching means for a door comprising a keeper having an open-ended slot, a resilient bar extending parallel to the side of the door and rigidly secured thereto at its end remote from said keeper, together with a rod extending through the door and having a handle at either side of the door, said rod being rotatable and having means engaging said bar to spring the same and move the free end thereof to engage and disengage said keeper.

These and other objects and advantages of the invention will be fully set forth in the following description made in connection with the accompanying drawings, in which like reference characters refer to similar parts throughout the several views, and in which:—

Fig. 1 is a view in front elevation of the door with the invention applied thereto;

Fig. 2 is a view in front elevation of the mechanism shown on an enlarged scale, some

parts being indicated in different positions in dotted lines;

Fig. 3 is a horizontal section taken on line 3—3 of Fig. 2 as indicated by the arrows;

Fig. 4 is a vertical section taken on line 4—4 of Fig. 2 as indicated by the arrows, and

Fig. 5 is a vertical section taken on line 5—5 of Fig. 2 as indicated by the arrows.

Referring to the drawings, a door 10 is shown mounted to swing upon the hinges 11 and adapted to close an opening in the frame 12 of the building.

In accordance with the present invention, a keeper plate 13 is provided which extends outwardly substantially at right angles to the side of the frame 12, and in the embodiment of the invention illustrated said keeper is shown as set into the edge of the door frame and secured thereto by a plurality of screws 14 extending through openings in said keeper plate. Said plate 13 has an open ended vertical notch or slot 13a therein and its surface 13b adjacent said slot extends upwardly in a curve to the edge of said slot thus forming a cam surface. Said keeper has a hole 13c extending therethrough below the slot 13a. A plate 15 of general rectangular shape is provided and secured flat against the side of the door 10 by a plurality of spaced screws 16 extending through holes in said plate, the screws 14 and 16 preferably being countersunk in their respective plates. Plate 15 extends to the edge of the door 10 and has an end portion 15a extending outwardly from said door substantially at right angles, said portion having a vertically extending elongated slot 15b therein which, when the door is in closed position, substantially aligns with the slot 13a. Portion 15a also has a hole 15c extending therethrough below the slot 15b adapted to align with the hole 13c in the keeper plate 13 when the door is in closed position. Portion 15a also has a hole 15d therethrough and plate 15 has a hole 15e therethrough, which holes are used when the plate 15 is used in a reverse position to that shown in Fig. 2. A bar 17 is provided, which bar is of resilient material and has a flat portion at its end remote from keeper 13 which is rigidly secured to the plate 15 by any suit-

able means, such as the rivets 18. The bar 17 has a portion 17a adjacent its attached end which is of rectangular shape in cross section with its long side extending at right angles to the surface of plate 15. The free end of the bar 17 is also substantially rectangular in cross section, but has its long side extending vertically, the free end of said bar 17 extending through slot 15b. A rod 19 extends through and is journaled in the plate 15, the door 10, and a plate 20 secured to the side of the door opposite plate 15 by the screws 21. Rod 19 has formed at one end a handle member 22 disposed at the outer side 15 of the door and slightly beyond the outer side of the bar 17. Rod 19 is threaded at its end opposite handle 22 and extends through a handle member 23 similar to the handle 22. A nut 24 is threaded on the end of rod 19 and holds handle 23 in place. A cam member 25 is secured to rod 19 adjacent plate 15 and beneath bar 17, said member 25 having a top surface on which bar 17 rests, said member 25 lifting said bar when it is rotated by rotation of rod 19 and handles 22 or 23. In Fig. 1 the door is shown in closed position and the lock 26 of padlock form is shown having its bail extending through holes 13c and 15c in members 13 and 15 thus locking the door in closed position.

In operation, when the door is in closed and latched position the parts will occupy the positions shown in the drawings. At this time the end of bar 17 projecting beyond the portion 15a of plate 15 is seated in the slot 13a of the keeper 13. When it is desired to release the latch, one of the handles 22 or 23 will be rotated and rod 19 and member 25 will be rotated, the latter engaging bar 17 and springing the same upwardly so that the free end thereof moves above the top of slot 13a of the keeper. The door can then be opened. The bar 17 can be raised in the same manner to move the same to latching position, or if the door is slammed or pushed to closed position bar 17 will cam up on surface 13b and drop into the slot 13a. It will be seen that bar 17 comprises a combined spring and latch. It will be noted that bar 17 is spaced from plate 15 and hence from the side of door 10 throughout substantially all of its movable part. If water or moisture should accumulate on plate 15 and be frozen thereon, it will not affect the bar 17 and the latter will thus not be frozen or frosted in locked position. It will be noted that the latch can readily be applied to doors of different thickness on account of the adjustment given by the threaded end of rod 19 and the nut 24 thereon. It will be seen that the latch is reversible and could be applied to the left hand side of a door as well as the right hand side as shown in Fig. 1. When so used, the rod 19 would extend through hole

15c in plate 15 and hole 15d would be lowermost and adapted to receive a lock.

From the above description it is seen that applicant has provided a very simple and efficient latch for a door and one particularly adapted for heavy doors, such as barn or garage doors. The lock comprises very few parts and is simple and rugged in construction. The same is constructed so that it will not be affected by a collection of ice on the door and the same is very easily applied and will suit doors of different thickness. The device has been amply demonstrated in actual practice and found to be very successful and efficient.

It will, of course, be understood that various changes may be made in the form, details, proportions and arrangement of the parts, without departing from the scope of applicant's invention, which, generally stated, consists in a device capable of carrying out the objects above set forth, in the novel parts and combinations of parts disclosed and defined in the appended claim.

What is claimed is:

A latch for a door having in combination, a plate secured flat against said door having an end portion adjacent the end of said door extending outwardly therefrom and having a vertically disposed elongated slot therethrough, a keeper secured to the door frame and extending outwardly therefrom having an open ended slot therein, a resilient latch bar rigidly secured to said plate at its end remote from said keeper, said bar extending through said first mentioned slot, a rod extending through said door below said latch bar and having handles secured at the ends thereof, and means on said rod adapted to engage said latch bar and spring the same to move the free end thereof upwardly to engage and disengage said keeper.

In testimony whereof I affix my signature.

ALBERT HOLLEN.
